UNITED STATES PATENT OFFICE

110,426

DESIGN FOR A DISPLAY BOX

John Edward Thebaud, Philadelphia, Pa.

Application January 30, 1937, Serial No. 67,356

Term of patent 3½ years

To all whom it may concern:

Be it known that I, John Edward Thebaud, a citizen of the United States, residing at Philadelphia, in the county of Philadelphia and State of Pennsylvania, have invented a new, original, and ornamental Design for Display Boxes, of which the following is a specification, reference being had to the accompanying drawing, forming part thereof.

The figure is a perspective view of the display box, showing my design.

The characteristic feature of the design resides in the contour of the cut out sides of the box, as shown.

I claim:

The ornamental design for a display box, as shown and described.

JOHN EDWARD THEBAUD.
